ABSTRACT OF THE DISCLOSURE

A deep-well pump having at least three principal elements, that is a transfer valve having a control valve, a reciprocating pump, and one set of six interconnecting pipes. The pipes include four pipes connected between the transfer valve and the pump and two pipes connected between the control valve and the pump. The system has three external pipes connected to the pump through the transfer valve that is reciprocated by action of the control valve moving in response to movement of the pump. The three external pipes include a pipe for the high pressure operating fluid, a pipe for pumping up the ground liquid and de-energized operating fluid, and an intake pipe for sucking in the ground liquid. The transfer valve controls at least the three external pipes and the four interconnecting pipes, and is designed to withstand extremely high pressures. The pump piston may have a drill rod and drill head at its lower end, whereby the pump piston will reciprocate the drill head to drill the well.

Pumping-up of a liquid from a well as deep as 3000 meters by an ordinary type pump has been considered to be impossible because of excessive elongation of the operating rod due to the weight of the rod itself and the weight loaded upon the end portion of the rod. For example, a rod of one inch in diameter and 3000 meters in length will, by itself, have a weight amounting to 13.5 tons. When equipped with fittings, the gross weight of the rod may well exceed 15 tons. In addition, when this is considered together with the weight of the liquid to be pumped up, it will be readily understood by pumping-up of a liquid from such a deep well by a pump of an ordinary type is impossible.

Various attempts have been made, therefore, to provide means to accomplish pumping-up of ground liquid in such a deep well by the use of liquid or pneumatic pressure. However, most of these pumps now in use are single-acting pumps with complicated mechanism, and various difficulties have been encountered in actual operations. Another factor which constitutes a problem in deep-well pumps is the fact that the static pressure of a water column gains one atmospheric pressure for every additional column of 10 meters. In a well which measures a depth of several thousand meters, the static pressure at the bottom of the well would be several hundred atm. So far in the past, there has been made no consideration to provide such valves and valve seats that can cope with this enormous static pressure. Ordinary ball valves or plane valves have been used in conventional deep-well pumps to resist the pressure of several hundred atm. During operation in an ultra-deep-well, it is no easy task to replace or repair the valves of a pump, and therefore, valves and valve seats which are immune against static pressure are just what are desired, theoretically. However, it may not be an exaggeration to say that there has been developed as yet no means to immunize valves and valve seats to meet with the requirements in actual operations. Accordingly, boring of an ultra-deep well is still in a stage to be developed.

2

It is, therefore, an object of the present invention to provide a double-acting deep-well pump to be actuated by fluid pressure which not only perfectly satisfies such basic requirements as described above but also renders economy and practicality. Further, the present invention contemplates to provide a continuously operatable boring machine unit with a drill head attached to the lower end of the piston of the pump of the present invention to realize simultaneous combined performances: boring an ultra-deep well while recovering the sludge carried by the water to the ground surface.

The primary object of the present invention is to provide a transfer valve that overcomes the above-mentioned disadvantages.

As an example, the specification describes a deep-well pump with such a valve, a cascade system employing the pump and valve combination, and a deep-well boring device based upon the principles of the present invention.

The high pressure operating medium to be used in the pump of the present invention is a fluid which is energized on the ground. In the case of pumping up oil, a part of the pumped-up crude oil may be used as a medium. Natural water or air which is readily available on the ground may also be used. It has been demonstrated from practices as well as from experiments that in case air is used as a medium, the length of time needed for the performance of changeover valves may be reduced, and therefore, in certain cases, the use of air is found to be more advantageous.

In the pumps of the present invention, conventional plane valves or ball valves are not used. But, indeed, a principle to realize complete immunization against the static pressure of the water column has been developed. In addition, the valves used in the pumps of the present invention need not be made of metal. Another feature of the present invention is that smooth action and a longer life of pumps is insured. Still another feature of the present invention is that the valves may be made of a plastic material which may be either acid-proof or alkaline proof depending upon the nature of the liquid to be pumped up.

A further object of the present invention is to provide an apparatus for pumping liquid actuatable by fluid pressure comprising a double-acting pump, a transfer valve for controlling control fluid for the pump and the liquid to be pumped out, and control valve means for actuating the control valve, said pump comprising two cylinders disposed in symmetrical relation to each other and having in common a partition plate and a piston rod, each cylinder comprising a wall at an end opposite to said partition plate, a piston carried by said piston rod, an operating pressure fluid orifice located close to the partition plate, a communicating pressure fluid orifice located between said piston and said partition plate but close to said piston at the position when said piston stops at the extreme end near said wall, and a ground-liquid orifice located between said piston and said wall at the same position, whereby ground liquid is sucked in and pushed out alternately through the ground-liquid orifices respectively by the movement of the pistons in the cylinders as actuated by the pressure fluid which is alternately supplied into the cylinders through the operating pressure fluid orifices and the communicating pressure fluid orifices.

The foregoing objects as well as other objects and advantages of the present invention may be more clearly understood by reference to the following detailed description when considered with the drawings in which:

FIG. 1 of the drawings is a ground unit including a fluid pressure generator for a fluid pressure-driven double-acting deep-well pump of the present invention;

FIGS. 2 and 3 are sectional elevations of a double-acting pump structure provided with valves, illustrating

the principle of the present invention, while FIG. 2 is a somewhat schematic sectional view illustrating the relationship between the valves, the piston and the liquid introduction orifices at the initial stage of the upward movement, FIG. 3 is another somewhat schematic sectional view showing the relationship between the valves, the piston and the liquid introduction orifices at the initial stage of the downward movement;

FIG. 4 is a somewhat schematic sectional view of an example of the pump of the present invention, illustrating the dimensional relationship between the orifices of the changeover gate valve unit and the movable valve disc bodies;

FIGURE 5 is a sectional view of the outer cylindrical shell of the pump, with the inner moving parts and the partition plates removed, taken along line V—V in FIGURE 8;

FIGURES 6 and 7 are sectional views of the pump taken along lines VI—VI and VII—VII in FIGURE 2, respectively, and the differences between the number of orifices and pipes compared with those shown in FIGURE 2 will be described in detail later;

FIGURE 8 is a developed view of the outer pump case and the valve taken along line VIII—VIII in FIGURE 7;

FIGS. 9 and 10 are diagrammatic illustrations of the system in applying a plurality of pumps of the present invention to a deep-well;

FIGS. 11 and 12 show examples of the structure of the pump for use in discarding de-energized operating liquid outside the pump unit; and

FIG. 13 is a pump of the present invention equipped with a drill head of a boring machine.

Now, in FIG. 1 of the drawing, numeral 1 represents a motor which drives a liquid pressure generator 2. Numeral 3 represents a tank for storing pumped-up ground liquid. A supply pipe for a high pressure operating medium is represented by h_1 , and a pipe for pumping-up liquid is represented by l_2 , which, in the following illustrations is given to indicate a passage or pipe for pumping up the mixture of ground liquid and the de-energized operating medium. Numeral 7 represents a pipe connecting the pressure generator 2 with the pipe h_1 . Numeral 8 represents a pipe for transferring liquid from the pipe l_2 into the tank 3. Numeral 5 represents a connecting metal fitting for bundling the pipes h_1 and l_2 and also for adding pipes. Numeral 6 represents a buffer unit for alleviating the fluctuations of the pressure in the high pressure operating medium line. Numeral 4 represents the ground surface, and numeral 9 represents the sectional view of the vertical opening of a well.

An operating medium or fluid which is highly energized by a pressure generator is supplied through the pipe h_1 to the underground pumping unit. De-energized medium, after completion of the role of sucking-up and forcing-up ground liquid, joins the pumped-up ground liquid stream and the mixture is forced upwards through the pipe l_2 to be stored in the tank 3. While h_2 corresponds to the return path of the de-energized operating medium, the medium in this case joins l_2 during its travel and returns to the tank 3, and accordingly, h_2 herein represents a phantom passage. Thus, the liquid introduction orifice h_2 which connects the tank 3 with the pressure generator may be interpreted as being a point at which the returning path of the mixture flow diverges from the pipe l_2 .

In FIGS. 2 and 3 of the drawings, numeral 40 represents a cylinder for a double-acting pump and a transfer valve unit. The portion defined between a lower end plate 39 and a partition plate 33 represents the double-acting pump, while the portion defined between the partition plate 33 and an upper end plate 54 constitutes a transfer valve unit. Pipes connecting said valve unit with said pump include six pipe lines including a pipe line l_a for ground liquid in a downward pump, a pipe line l_b for ground liquid in an upward pump, a pipe line h_a for high

pressure operating medium in a downward pump, a pipe line h_b for high pressure operating medium in an upward pump, an outlet pipe line s_a for the high pressure fluid to be used for shifting the sequences of the transfer valve unit at the terminating period of downward movement, and an outlet pipe line s_b for the high pressure fluid used for the operation of shifting the sequences of the transfer valve unit at the terminating stage of upward movement. In the drawings, l_1 represents a pipe for conducting sucking up ground liquid, l_2 a pipe for pushing up ground liquid, and h_1 an inlet pipe for conducting the high pressure operating medium. In the drawings, however, the return path h_2 for the operating medium that has been deenergized after completion of work joins l_2 and therefore it represents a phantom passage which is not shown in the drawings. These four pipe lines, however, represent high pressure lines h_1-h_2 and low pressure lines l_1-l_2 , constituting four terminal pipes. The above-mentioned six pipes for internal communication which are disposed between the pump and the valve unit constitute the passages of the fluid used for effecting the changeover of the connections in conformity with the upward and the downward movements of the pump piston by opening and closing the valve gates interposed between the four terminal pipes and the pump.

In FIGURES 2 and 3, the pump pistons 31, 32 that are connected together by rod 30 are shown in side view along with the control valves 42, 47, 52, and the movable disk bodies 48, 49, 50, 51 fixed on a common axially extending rod 44 forming intermediate gates 55, 56, 57, 58, 59. In the actual case, the orifices, three external pipes and six interconnecting pipes are three-dimensional, but have been shown in the drawing on a single plane in the manner of an electrical wiring diagram for purposes of illustration.

FIGURE 8 is a development view showing the relationship between the pipes and the orifices. For example, the indication $h_1(E_1E_2)$, $l_a(Z_2TKR)$ would express that the upper parts of twin segmental tubes are allocated to the twin pipes h_1 , while the lower half of the same is allocated to the twin pipes l_a and there are immediately below the twin orifices E_2 , the twin orifices E_1 of the pipes h_1 , the twin orifices Z_2 , T, K, R of the twin pipes l_a are in the different levels respectively. Here, the word "twin" means two substantially identical parts facing each other on diametrically opposed sides (refer to FIGURE 8).

A description of the transfer valve, which is a key point of the present invention, will follow. As is clearly understood from FIGURES 5, 6, 7 and 8, the outer shell of the actual device, including the transfer valve, the control valve and the pump proper, comprises two coaxial cylinders 40 and 60 with the vertical partition plates 61 and the transverse partition plates 62 and/or 63 in the case that the deenergized operating fluid is to be directly discarded into the outside of the outer shell through the twin orifices Z_1 , Z_2 .

The annular space between the cylinders 40 and 60 is divided into twelve segmental tubes. If we take as twins two segmental tubes facing each other on diametrically opposed sides, we have then six sets of the twins around the cylinder 40. As shown in FIGURE 8, if we divide three sets of these twins by the plates 62 for the purpose of economical usage of the annular space, we have nine twins into which the three external pipes and the six interconnecting pipes are assigned. The requirement on the assignment is such that: three external pipes h_1 , l_1 , l_2 and four interconnecting pipes l_a , l_b , h_a , h_b connecting with the transfer valve comprises the twin pipes respectively, while two interconnecting pipes S_a and S_b connecting with the control valve comprise single pipes, respectively.

In FIGURES 5, 6, 7 and 8, there are the twins of h_b , l_b , l_1 , h_a , l_a , l_2 , respectively, two sets of twins of h_1 , and single pipes of S_a and S_b . Among three external pipes,

two of the twins of h_1 and the twins of l_2 connected with the operating liquid pipe S_1 and the pipe for pumping up l_2 in FIGURE 1 respectively and the twins of the pipes l_1 connect with the ground liquid well.

Referring to FIGURE 8, the twins h_b have the twins of the orifices G, I and Q, and the single orifice D for the control valve; the two twins h_1 have the twins of the orifices E₂, E₁; the twins l_b have the twins of the orifices Z₁, U, L, S; the twins l_2 have the twins of the orifices Y₂, Y₁; the twins l_1 have the twins of the orifices J₁, J₂; the twins h_a have the twins of the orifices F, H and P, and the single orifice C for the control valve; the twins l_a have the twins of the orifices Z₂, T, K, R. Single pipe S_a has the single orifice A and the single orifice M, and the single pipe S_b has the single orifice B and the single orifice N.

The orifices may be classified as four kinds: A, B, C, D (each of them being a single orifice) for the control valve; sixteen kinds G, E₂, F, E₁, H, Z₁, I, Z₂, U, Y₂, T, Y₁, K, J₁, L, J₂ (each of them being twins) for the transfer valve; and six kinds S, N, Q, P, M, R (each of them being twins except single orifices N and M) for the pump proper. These orifices are, as in FIGURE 8, arranged in each pipe, and on each different level, while the orifices of the transfer valve being combined as G-E₂, F-E₁, H-Z₁, I-Z₂, U-Y₂, T-Y₁, K-J₁, L-J₂ are arranged on each of eight different levels and at regular intervals. And, when these combined orifices are engaged with the disks of the movable disk body of the transfer valve, this results in the disconnection between the external pipe and the interconnecting pipe. When these orifices are engaged with the gates, it results in the interconnection between them.

The movable disk body of the transfer valve comprises disks 48-51 forming the gates 55, 56, 57, 58, 59 at regular intervals and mounted on the axially extending rod 44 common with the axis of the control valve.

Thus, the transfer valve comprises said cylindrical shell with said connected orifices, and said movable disk body.

The control valve built in the common cylindrical shell comprises the orifices A, B, C, D; the pistons 52, 47, 42 which are fixed with the rod 44 common with that of the transfer valve, the chamber 53 between the end plate 54 and the piston 52, the chamber 46 between the plate 45 and the piston 47, the chamber 43 between the plate 45 and the piston 42, and the chamber 41 between the piston 42 and the plate 33. In this valve, it is noticed that the diameter of the piston 52 or 47 is larger than that of the piston 42.

The movable disk body of the transfer valve is put in reciprocating motion with a definite stroke by the piston of the control valve. While the four groups of the combined orifices F-E₁, I-Z₂, T-Y₁ and L-J₂ are closed by the disks 51, 50, 49 and 48 respectively, another four groups of the combined orifices G-E₁, H-Z₂, U-Y₁ and K-J₂ are connected by the gates 59, 58, 57 and 56 respectively, and vice versa.

Again returning to FIGS. 2 and 3, the portion on each side of the partition plate 36 represents a single acting pump capable of making upward and downward movement, respectively. Numerals 31 and 32 represent downward and upward pistons, respectively. Numeral 30 represents a piston rod for connecting said pistons. P and Q represent orifices for forcing-in a high pressure operating medium for effecting downward or upward movement, respectively. Likewise, R and S represent an outlet and an inlet of ground liquid. Similarly, M and N represent liquid introduction orifices for transmitting a part of the operating pressure to the control valve when said piston has reached the position of terminating movement. Numerals 34 and 35 represent chambers for pumped-up liquid, and likewise, numerals 37 and 38 represent chambers for high pressure operating fluid.

In FIG. 4 is shown an example of actual structure in which an extra opening a is given. However, this extra opening should not give rise to said undesirable intercommunication between the high pressure system and the low pressure system. In the drawing, the diameter of the orifice F-E₁ is given a dimension of d_0+a as against the diameters d_0 for all the other orifices, and among the movable valve disc bodies 48, 49, 50 and 51, three valve disc bodies other than 50 are given a uniform thickness of t_1 , while the valve disc body 50 is given the thickness of t_1+a , wherein this a represents the amount left out of the overlap of the orifice and the valve disc. This discrepancy in the diameters is given to prevent the intercommunication between the orifice F-E₁ which has a diameter elongated by a and the low pressure orifice H-Z₁ which is communicated by an interconnecting pipe h_a ; in other words, the dimensional discrepancy is provided to satisfy the requirement that at the starting of opening of the orifice F-E₁, at least the orifice H-Z₁ must complete closing. Hence, the necessity that while all of the five gates except the gate 58 are equally of a height d_1 , the gate 58 alone should have a height: $d_1-a=d_2$. In this drawing, there is shown an example in which the range of the stroke w is designed to be consistent with the height t_1 .

FIG. 2 shows an initial stage of an upward movement, and the high pressure operating fluid pushes up the piston 32 in the order of $h_1-E_2-G-h_b-Q$. The ground liquid in the chamber 35 is forced upward in the order of $S-l_b-U-Y_2-l_2$. The operating liquid which was energized and which is now de-energized joins the ground liquid and is forced upward in the order of $P-h_a-H-Z_1-l_b-U-Y_2$. Also, ground liquid is sucked into the chamber 34 by the reverse route of $R-l_a-K-J_1-l_1$.

Now, let us consider the action of the valves at this moment. Because the pipe line h_b alone is being energized under a high pressure, the passage between the orifice D and the chamber 43 of a control valve gets energized so that the movable valve disc body may be held at a lower position. When the piston 32 reaches the position of ending movement, intercommunication between Q-N takes place, thereby imposing a pressure upon the piston 47 of said control valve in the order of S_b-B-46 . At this moment, the chamber 43 is being subjected to a pressure as described above, but, owing to the fact that the diameter of the piston 47 is larger than that of the valve piston 42, said piston 47 will start an upward movement. This will reverse the opening and closing action of the orifices G-E₂ and F-E₁ and will cause the pipe line h_b to be de-energized while the tubular passage or pipe h_a is energized. This is followed by the energization of the chamber 41. Thus, the valve disc bodies complete their upward movements and hold this state. This position is shown in FIG. 3. The opening and closing sequences of the orifices of the transfer valve are shifted, and the pump pistons start a downward movement. More particularly, the orifice P is energized to push the piston 31 downwards. The description of the displacement of the liquid in each of the chambers of the pump at this moment is omitted, since the movement of the liquid will be apparent from the drawings when considered together with the previous description concerning the upward movement of the liquid. When the pump piston reaches the ultimate end of the downward movement, a pressure will be transmitted into the chamber 53 in the order of $P-M-S_a-A-53$, and the valve disc body will move downwards to return to the state as shown in FIG. 2, to be followed by the starting of upward movement of the piston 32. Thus, so long as the high pressure operating fluid h_1 continues to be energized, the pump will repeat its reciprocating movements, thereby accomplishing the continuous pumping-up of liquid as aimed at.

As described above, for a transfer valve unit of a double-acting pump which pumps up ground liquid by the use of a high pressure operating medium, it is theoretically necessary that the four terminal pipes, namely, the outlet

and inlet pipes h_1 and h_2 for the high pressure medium, the pipe l_1 for sucking up ground liquid, and the pipe l_2 for pumping up ground liquid are connected with said transfer valve. In the case where a liquid similar in quality with the ground liquid is used as a high pressure operating medium, however, said four passages or pipes may be reduced to three by utilizing the pipe line of pumping-up ground liquid as the return path of the operating medium. Also, in case water, air, etc. is used as a high pressure operating medium, it is easy to arrange the structure so that such medium may be discarded outside the pump immediately after being de-energized, if required. To describe this in more detail, in the case, for example where water is abundantly available on the ground and where such water is used as an operating fluid, the de-energized water which has finished the role as high pressure operating fluid should be discarded outside the pump by insulating the passages H-Z₁ and I-Z₂ of the transfer valve by the upper partition plate 62 and a lower partition plate 63 from the pipes h_1 , l_a and l_b as shown in FIGS. 11 and 12. Also, in utilizing compressed air, or when the pumps of the present invention are used in cascade form, there may be cases where it is desirable from the structural point of view to discard the operating fluid immediately after being de-energized in the manner as described above.

Next, the cascade arrangement of the pumps of the present invention will be described. In case of a well having a depth as great as 3000 meters, the high pressure operating medium requires to be given a pressure of at least several hundred atms. This will mean that every portion of the entire unit becomes costly. Whereas, if the pumps of the present invention are used in cascade, meaning that by dividing the overall height of a well into equal parts numbering n , and by placing at each point of the division one pump made of a material which can resist the pressure of $1/n$ of the overall height, by arranging each pump in vertical cascade form, by connecting a pressure inlet pipe of each pump with the main high pressure operating fluid supply pipe extending from the fluid source, and also by connecting a suck-up pipe of any pump with a push-up pipe of another pump just below said any pump there is provided a great advantage that every portion of the overall unit has only to resist a low pressure. FIGS. 9 and 10 connote this principle. FIG. 9 illustrates the principle of the pump of the present invention, wherein V denotes a valve; P a pump; and 61C six internal communication pipes i.e. four interconnecting pipes and two communicating pipes. Since this pump has four terminal pipes: h_1 , h_2 , l_1 and l_2 as described in the above, if the push-up pipe l_2 of an arbitrary pump among the pumps numbering n is connected with the sucking pipe l_1 of the adjacent pump located above said arbitrary pump, and if pumps numbering n are connected in vertical cascade form, and also if de-energized liquid which has completed work is designed to be directly discarded outside the pump in such manner as is illustrated in FIGS. 11 and 12, a pump for an ultra-deep well can work without being exposed to an enormous external static pressure.

Next, the pump of the present invention equipped with boring head will be described with reference to FIG. 13.

In FIG. 13, a drill rod 65 and a drill head 66 are attached to the lower end of the piston 31. By the action of the piston which is operated by the liquid pressure, the drill is operated. The drill thus will proceed deeper into the ground. The sludge produced by the drilling can be carried up to the ground by the ground liquid. On the other hand, it is easy to mechanically or electrically check or detect the amount of boring relative to the fixed position on the ground where the pump unit is located.

Therefore, when the detector senses that a predetermined depth has been drilled, the pump can be lowered

to the level attained by the boring, and thus continuous boring of the well can be attained. By repeating this operation either manually or by suitable automatic means, continuous well-boring operation can be realized. In this case, it is also possible from practical point of view to conduct the pushing-up of ground liquid by the action of the piston 32 alone, without the end plate 39 and the liquid introduction orifices R, K and T associating with the pipe line l_a , for example, among the communicating pipe lines l_a and l_b .

It is to be understood that various modifications may be conceived without departing from the substantial properties of the present invention. The above described examples are intended merely to illustrate some of the important aspects in certain selected embodiments of the present invention.

What is claimed is:

1. An apparatus for pumping liquid actuatable by fluid pressure comprising a double-acting pump, a transfer valve means for controlling control fluid for the pump and the liquid to be pumped out, and control valve means for actuating the transfer valve means; said pump comprising two cylinders disposed in symmetrical relation to each other and having in common a partition plate and a piston rod; each cylinder comprising a wall at an end opposite to said partition plate, a piston carried by said piston rod, an operating pressure fluid orifice located close to the partition plate, a exhausting pressure fluid orifice located between said piston and said partition plate but close to said piston at the position when said piston stops at the extreme end near said wall, and a ground-liquid orifice located between said piston and said wall at the same position; said transfer valve unit consisting of a cylinder, a rod, a group of disk bodies carried by said rod and spaced from each other at predetermined intervals, a plurality of gates formed by the spaces between said disk bodies, a plurality of orifices disposed in the cylinder; said control valve means having a cylinder, a piston in said cylinder, a wall between said control valve means and said transfer valve means, and a piston rod drivingly connected to and extending integrally from said transfer valve rod through said wall provided between said transfer valve and said control valve; said apparatus further comprising four terminal pipe means consisting of two pipe means for conducting high pressure operating fluid, pipe means for conducting sucked up ground liquid and pipe means for conducting pushed out discharged ground liquid, each of said pipe means being connected with said transfer valve means; two ground liquid interconnecting pipe means connecting respectively said ground liquid orifices with said transfer valve means, two operating fluid interconnecting pipe means respectively fluid connecting said operating pressure fluid orifices with said transfer valve means; and two exhaust fluid pipe means providing fluid communication between said exhausting pressure fluid orifices, respectively, and said transfer valve means.

2. An apparatus according to claim 1, wherein said transfer valve means orifices include two high pressure operating fluid orifice means, one pair of which are slightly larger in the axial dimension, with respect to said transfer valve means rod, than the other pair, and both pairs being connected with said two pressure fluid interconnecting pipe means; said transfer valve disk bodies including one disk body means for controlling the exhaust operating fluid and being slightly larger in the axial dimension than the other disk bodies, to constitute means for closing one pair of orifice means for the high pressure operating fluid immediately prior to opening the other pair of orifice means for the high pressure operating fluid.

3. A pump, comprising: fluid operated pump means; a transfer valve having a cylinder with a plurality of orifices, a plurality of disks slideably arranged in said cylinder for valving said orifices and a rod drivingly con-

necting said disks; three external pipe means fluid communicating with corresponding orifices and six interconnecting pipe means for providing fluid communication between corresponding orifices and said pump means, each of said pipe means and corresponding orifices including substantially identical pipes and orifices diametrically disposed on opposite sides of said cylinder; said orifices being arranged, in planes generally perpendicular to said rod, to provide fluid communication between corresponding ones of said external pipe orifices and said internal pipe orifices, respectively; said disks being spaced on said rod at axial distances substantially equal to the axial distances between said planes; said orifices and said disks being spaced axially from each other so that at one axial position of said disks one half of said external pipe orifices will be fluid connected with the corresponding one half of the interconnecting pipe orifices, and at another axial position of said disks the other half of said external pipe orifices will be connected with the other half of said interconnecting pipe orifices.

4. The device of claim 3, including control valve means for shifting said disks axially between said two positions, including wall means and piston means forming two piston-cylinder chambers of relatively large effective cross section and two piston-cylinder chambers of relatively small effective cross section; said transfer valve means having four orifices connected respectively with said cylinders; said piston means being drivingly connected to said transfer valve means for relatively shifting said disks; said pump means being a double acting pump reciprocable between two positions corresponding to the reversal of direction; said transfer valve selectively supplying operating fluid to both one of said relatively small chambers for urging said transfer valve means in one direction and said pump means for driving said pump means in one direction toward one of its positions, and for supplying operating fluid to both the other of said small chambers for urging said transfer valve means in its other direction and said pump means for driving said pump means in the other direction toward the other of its positions; valve means responsive to the position of said pump means for supplying operating fluid to one of said relatively large chambers for driving said transfer valve means in its said other direction when said pump means is closely adjacent to its said one position and for supplying operating fluid to the other of said relatively large chambers for driving said transfer valve means in its one direction when said pump means is closely adjacent to its said other position.

5. The device of claim 4, wherein said transfer valve means is operatively fluid interposed between said pump means and said three external pipe means; one of said external pipe means supplying operating fluid, the second of said external pipe means delivering the liquid pumped by said pump means and the third of said external pipe means providing the suction liquid for said pump means.

10 6. The device of claim 5, including at least one additional set of pump means, transfer valve means and control valve means substantially identical to a first set of said first mentioned pump means, transfer valve means and control valve means; said sets being serially arranged with one of the outermost sets having its delivering external pipe means being for connecting to a reservoir, the other outermost set having its suction external pipe means being for connection to a source of fluid to be pumped, the remaining delivering external pipe means being connected to the remaining suction external pipe means, respectively, of adjacent sets, and said operating fluid external pipe means being connected in parallel.

15 20 25 7. The device of claim 5, wherein said pump means has a piston and piston rod; and including a drill head drivingly connected to said pump means piston rod to pump up the sludge that issues from the drilling, together with the ground liquid and any liquid poured from the ground surface into the well bottom.
